UNITED STATES PATENT OFFICE

149,106

DESIGN FOR AN EDUCATIONAL APPLIANCE

Esther Berman, Chicago, Ill., now by judicial change of name Esther Berryman

Application July 1, 1946, Serial No. 131,225

Term of patent 7 years

(CL. D25—1)

To all whom it may concern:

Be it known that I, Esther Berman, a citizen of the United States, residing at Chicago, in the county of Cook and State of Illinois, have invented a new, original, and ornamental Design for an Educational Appliance, of which the following is a specification, reference being had to the accompanying drawing, forming part thereof.

I claim:

The ornamental design for an educational appliance, as shown.

ESTHER BERMAN.

Now by Decree of Court Esther Berryman.
